UNITED STATES PATENT OFFICE.

FRANK W. LARC, OF PANUCO, MEXICO.

BOILER-TUBE-CUTTING DEVICE.

Application filed July 13, 1925. Serial No. 43,890.

The present invention appertains generally to cutting devices, and more particularly to that class of devices for cutting the tubes out of boilers.

- 5 The principal object of the invention is to provide an adjustable cutter, whereby the tube may be cut a distance from the end thereof or at the end thereof, as may be desired.
- 10 A further object of the invention is to provide a device of this nature, which is possessed of an exceedingly simple and efficient construction, one which is reliable in operation, inexpensive to manufacture, 15 strong and durable, not liable to readily get out of order, easy to manipulate and adjust, and otherwise well adapted to the purpose for which it is designed.

Another very important object of the invention is to provide a tool of this nature, consisting of a suitable number of parts, which are adapted to be readily assembled or disassembled.

With the above and numerous other objects in view, as will appear as the description proceeds, the invention resides in certain novel features of construction, and in the combination and arrangement of parts as will be hereinafter more fully described and claimed.

In the drawing:

Figure 1 is an elevation of one embodiment of this device, showing the same located in a boiler tube, the latter being shown in section.

Figure 2 is an enlarged transverse section, taken substantially on the line 2—2 of Figure 1, looking in the direction of the arrows.

Figure 3 is a longitudinal section there- 40 through.

Figure 4 is an end elevation of the mandrel.

Figure 5 is a detail sectional view on an enlarged scale, showing the means for holding leaf springs used with this embodiment.

Figure 6 is a detail elevation of one end of the wedging pin.

Figure 7 is a detail perspective view of one of the springs.

Figure 8 is an end elevation of the retaining collar for the knives.

Figures 9 and 9^a are perspective views of the cutting knife.

Figure 10 is an elevation of a spacing ring 55 being a modification of that shown in Figure 1.

Figure 11 is a transverse section there- 60 through taken substantially on the line 11—11 of Figure 10, looking in the direction of the arrows.

Figure 12 is a longitudinal section there- 65 through.

Referring to the drawings in detail, and more particularly Figures 1 to 9^a inclusive, it will be seen that a boiler has been indicated at B, provided with the usual tube T, held against longitudinal displacement by the end flange F. A mandrel 5 is provided with a cylindrical shaped outer surface having a plurality of indentures 6 therein, arranged in a spaced series of circles, as is evident from an inspection of Figure 1. The interior of this mandrel 5 is provided with a longitudinally extending tapering bore 7, having extending from its inner end 70 a plurality of longitudinally extending grooves 8, which in the present instance, are three in number, but, of course, the number thereof may be varied, as desired. These grooves 8, are deeper at their ends than at 75 their intermediate portions, because of the tapered bore 7, as is indicated to advantage in Figure 3, and form compartments for receiving leaf springs 9, the inner ends of which are fastened by L-shaped bolts 10, the nuts associated therewith, being embedded as indicated at 11, in the outer surface of the 80 mandrel. It is not necessary that the entire bore 7 be tapered, as it may be cylindrical at the outer end thereof, as is indicated at 85 12. This mandrel is adapted to be extended into the boiler tube T, and the distance at which it is extended within the tube is controlled by an abutment ring 13, adapted to 90 be exposed about the mandrel, as shown in Figures 1 and 3. A plurality of set screws 95 or bolts or the like, are threaded radially through the ring, for engagement with indentures 6. By providing these indentures as described, in a plurality of circularly arranged series, it will be seen that the ring 100 may be moved longitudinally of the mandrel and locked in engagement at desired points, by engaging set screws 13' in the proper indentures. The inner end of the mandrel 5 is provided with a plurality of radially extending recesses 14, arranged in coincidence with the grooves 8, for the reception of blades or knives 15, which are constructed with curved shoulders 16 at their inner ends 105 cutting edges 17, at their outer edges, and slots or openings 18 adjacent the shoulders 110

16. The shoulders 16 are adapted to extend outwardly from the mandrel as indicated in Figure 3, while the blades, that is, the bodies thereof, are located in the recesses 14, and the springs 9 extend through the slots 18 thereof. These springs 9 are tensioned to hold the knives in a predetermined position, preferably so that the knives are just slightly projected beyond the outer surface of the mandrel.

15 A retaining collar 20 is provided with a tapered bore 21, and bolt holes 22, so that it may be attached to the inner end of the mandrel with the bore 21 in alignment with bore 7, by means of bolts 23 passing through the bolt holes 22 and threadably engaged with the mandrel. The end of the collar 20, adjacent the inner end of the mandrel 5 is provided with recesses 24 radiating from the bore 21, in coincidence with the recesses 14, for the reception of the shoulders 16 of the knives 15, it being noted that recesses 24 are not as wide as recesses 14, for the reason that the shoulders 16 are not formed as wide as the bodies of the knives. This, however, is clearly a matter of preference, and may be varied. An operating wedge pin is indicated generally at 5, and includes a cylindrical body 26, having the tapered extension 30 27 at one end, and a transversely extending handle 28 extended through the other end. The tapered extension 27 is adapted to be inserted in the mandrel through the collar 20, for the purpose of engaging the inner ends or shoulders of the blades 15, and, of course, when driven in, by a sledge hammer or the like, will project these blades outwardly from the mandrel into engagement with the inner surface of the tube T. This process is continued, as will be readily understood by those skilled in this art.

45 Particular attention is now called to Figures 10 and 12 inclusive, wherein applicant has shown a modified form of the adjustable ring, which may be used with the embodiment of the invention just disclosed, in place of ring 13. This improved adjustable mandrel retaining device consists of a ring 30, having screws 31 projected radially there- 50 through for engagement with the indentures 6 of the mandrel, and one side face thereof is recessed, as is indicated at 32, in Figure 12, for the reception of an inwardly disposed end flange 33, on the cylindrical body 34. This body 34 is slotted longitudinally, as at 35, for the purpose of saving material, and also for the purpose of forming sight openings, in order that the major portion 55 of the mandrel will be visible. The flange 33 is locked in the recess 32, by an annular member 36, held in engagement with the ring 30, by screws or other suitable fastening elements. With this retaining ring, it is

possible to so locate the mandrel 5, that the knives may sever the flange F from the tube T. The use of this ring 30, in place of ring 13, is quite evident, without a more detailed description or further illustration.

It will be apparent from the above that I have produced a device, which may be effectively used in cutting out tubes of a boiler, by one possessed of very little skill, because of the simplicity of the device, whereby it may be readily adjusted as desired, and is capable of being easily or quickly assembled or disassembled. The device is not liable to readily get out of order, and possesses great strength and durability. The present embodiments of the invention have been disclosed in detail, merely by way of example, and it is to be understood that numerous changes in the details of construction, in the materials, and in the combination and arrangement of parts may be resorted to, without departing from the spirit or scope of the invention as hereinafter claimed, or sacrificing any of its advantages.

Having thus described my invention, what I claim as new is:

1. A cutting tool of the class described, including a mandrel having a longitudinally extending bore and on one end provided with radially extending recesses, said bore of the mandrel being provided with longitudinally extending pockets, springs supported in the pockets, knives located in the recesses, a collar having radially extending recesses registering with the first mentioned radially extending recesses, said collar being provided with a bore registering with the bore of the mandrel, said knives being provided with shoulders extending into the second mentioned recesses, said springs having their extremities engaging the knives, and means slidable through the bore for projecting the knives.

2. A cutting tool of the class described, comprising a mandrel, having a longitudinally extending bore and on one end being provided with radially extending recesses, a collar having radially extending recesses registering with the first mentioned radially extending recesses, means for securing the collar to the mandrel, said collar being provided with a bore registering with the bore of the mandrel, blades disposed in the first mentioned recesses, and provided with shoulders extending into the second mentioned recesses, springs extending longitudinally through the bore of the mandrel, having one end fixed thereto and the other end engaging the blades, and means extendible through the bore for projecting the blades.

In testimony whereof I affix my signature.

FRANK W. LARC.
